ELECTRON TUBE

William Walter McGoffin, New York, N. Y.,
assignor of one-fifth to S. S. Baker, New York,
N. Y.

Application July 12, 1946, Serial No. 683,058

4 Claims. (Cl. 250—27.5)

1

This invention relates to electron tubes and more particularly to such a tube having a physically variable element for changing the operating conditions of the tube.

One of the objects of this invention is to provide means whereby the effective grid control area within the tube may be varied automatically according to the conditions to be measured so that the plate current flow or the operating conditions of the tube are similarly varied.

Another object of this invention is to provide a simple device for automatically amplifying an indication of temperature or other condition when such condition can be caused to produce movement of an element.

Another object of this invention is to provide a simple device for giving remote indications of a condition existing at the site of an electronic tube constructed according to the instant invention.

Still another object of this invention is to provide a means of automatic temperature control wherein changes of temperature can be caused to produce physical movement of an electron tube element which tube can thereupon directly control heat or cold producing devices so as to neutralize the change of temperature.

A further object of this invention is to provide an electronic device adapted to effect rapid micrometer measurements such as where the thickness of articles is to be determined rapidly and with precision.

Other objects of my invention will be apparent from the following description, it being understood that the above general statements of the objects of my invention are intended to describe and not limit it in any manner.

Referring to the drawings:

Fig. 1 is a schematic circuit diagram illustrating an embodiment of the invention particularly adapted to temperature indications and control.

Fig. 2 illustrates a modification of the grid structure shown in Fig. 1.

Fig. 3 is a schematic circuit diagram illustrating a modified embodiment of the invention.

Fig. 4 is a schematic circuit diagram illustrating another modified embodiment of the invention.

Fig. 5 is a front view of the grid structure of Fig. 4.

Fig. 6 is a schematic circuit similar to Fig. 4, but illustrating an electronic tube having a pair of anode structures so as to be adapted to push-pull operation.

The tube 10 in Fig. 1 is illustrated as being of

2

the ordinary three element type although, as will hereinafter appear, the invention can be adapted to multi-element tubes. The tube 10 is provided with a conventional anode or plate 11 and a cathode 12. The tube may be of the filamentary or indirect heated type although tubes having a cold cathode are well adapted to the invention.

The control grid 14 is constructed according to the invention herein as thermometer tubing 10 housing a supply of mercury in the column 15 of the bulb 16. As will be recognized, the mercury rises in the grid tubing in response to temperature increases. Grid 14 is illustrated as taking the form of a spiral glass tube surrounding the cathode 12. The physical shape, however, of the grid 14 may follow that of conventional grid structures as, for example, mesh structures, the difference being that the grid in the present invention is of continuous glass tubing or other 20 non-conducting material is hollow, and is provided with a supply of temperature responsive liquid, such as mercury. If desired, salt water, a sodium solution, cesium or rubidium, may be substituted for the mercury when conditions so 25 permit.

The column 15 may be as great as 4 inches in length so as to minimize the effects of tube heat. However, since the tube heat is practically constant, its effect can be calibrated or otherwise 30 provided for although in cold cathode tubes this is unnecessary. The spiral tubing comprising the grid 14 may be substantially thinner than that of ordinary thermometers since it is not obliged to withstand the pressures acting upon 35 conventional thermometers which are not disposed in a vacuum as is the grid 14 herein. The reduced thickness of the structure is furthermore advantageous in enhancing the effectiveness of the grid control.

Bias between the cathode 12 and grid 14 is provided in the form of battery 17, a tap 18 serving to vary the bias potential. It is apparent, however, that ordinary cathode bias such as may be provided by a cathode resistor, may be used. Tap 18 is connected to lead 19 which in turn is electrically connected to the mercury. This may be effected by providing a metal plug 20 in the wall of bulb 16 so that the lead 19 may be soldered thereto so as to effect contact with the 45 mercury. Alternatively, the lead 19 may be introduced into the bulb 16 and sealed with a conventional metal to glass seal.

The plate load takes the form of a resistor 21 which may have a conventional value such as in the neighborhood of 100,000 ohms. In practice,

resistor 21 may be a heat producing device which, if desired, can be caused to react upon the mercury so as to produce cut-off in the tube and de-actuation of the heat producing device. Plate voltage may approximate 150 volts although considerably higher voltages such as used in cathode and X-ray tubes may be used. Such higher voltages will decrease the effect of the glass tubing on the grid control system. Furthermore, alternating current may be used for tube operation whereupon said effect may be likewise decreased due to reduced impedance.

The operation of the tube 10 will be understood by those skilled in the art. Briefly, when temperature conditions are such that the mercury is low in the grid structure, the effective grid area will be small so that the electron stream between the cathode 12 and anode 11 is impeded very little by the presence of the grid. Should the mercury rise however, the mercury will control a larger area between the cathode and anode so as to serve as a more effective barrier to the electron flow inasmuch as the mercury is charged with the biasing potential. Should the mercury reach sufficiently high, it will introduce the bias voltage between the entire cathode and anode so as to approach or produce cut-off in the tube operation. The voltage required therefor will be determined by the specific tube employed since the characteristics of different tubes vary in a manner which is well known to those skilled in the art.

If the above circuit is utilized in a temperature oven, the effect on the electron stream by the rising or falling mercury may be utilized in operating a relay in the anode circuit for controlling temperature balancing devices such as refrigerators or heat producing devices. It is also feasible to substitute a temperature calibrated plate-current meter in the circuit in place of resistor 21 whereupon remote reading of the temperature existing at the location of the tube will be given.

In Fig. 2 is illustrated a form of grid structure wherein the bias voltage appears externally of the tubing so as to present a more effective grid control. Grid 25 is of the hollow glass construction described above and is provided with a supply of mercury in its bulb 26. Each half turn of the spiral tubing is provided with spaced metallic plates located exteriorly of the tubing but communicating with the inside thereof. Thus, metal plate 27, shown broken away may be formed by spraying metal around spiral portion 28 so as to deposit a metallic coat thereon. Portion 28 may have one or more minute openings communicating with the interior of the spiral tubing for receiving the sprayed metal therethrough so as to form an integral projection 27a with sprayed metallic plate 27 so as to effect electrical contact with the mercury. Thus, the potential of the mercury which is applied through the plug 29 is transferred to plate 27. Instead of the sprayed formation of plate 27, it is apparent that the plate in tubular form having an integral projection on the inner wall thereof, may be suitably heated so as to penetrate portion 28 with its integral projection and thereafter suitably fastened as by a metal to glass seal. The mercury will thereupon transfer the bias potential to the plate. Plates 30, 31, 32, 33 and additional plates follow successively up the spiral grade tubing and are mutually spaced by small sections of the glass tubing so as to be insulated from each other. Each of said plates is formed in a manner similar to that of plate 27 so as to communicate elec-

trically with the mercury disposed within the tube.

It will be recognized that as the mercury rises in the grid structure illustrated in Fig. 2, each half turn of the spiral grid will become successively charged with the bias potential so as to present a progressively higher grid control or barrier to the electron flow. The spacing between plates may be as small as desired in order to provide the required sensitivity in the device.

In Fig. 3 is illustrated a modified method of varying the effective grid area in accordance with the conditions to be measured. Tube 35 is again illustrated as being of the triode type, the anode 36 and cathode 37 serving the same functions as those in the previous embodiment. Grid 39 may be of the conventional metallic mesh and means are provided for swinging the grid in and out of the electron stream in varying degrees. Accordingly, a bell crank lever having the metallic arms 40 and 41 pivoted on pin 42 is connected to grid 39 so as to provide the grid with a swinging movement. Pivot pin 42 may be fixed in the base of the tube, the upper end of pin 42 rotatably supporting the bell crank lever. A spring 43 which is connected to a pin 44 likewise mounted in the base of the tube, is connected to lever arm 41. Thus, the normal position of the grid 39 is outside of the electron stream so that, in effect, the tube is a diode since the grid 39 is ineffective in varying the electron flow. As in conventional electron tubes, cathode 37 and anode 36 are substantially in longitudinal alignment. The alignment of the grid in the instant structure there-with is variable as disclosed. As the grid approaches alignment with the anode and cathode it tends to approach or produce cut-off in the tube. Lever arm 40 is of magnetic material such as steel and it may be of the permanent magnet type, if desired.

Arm 45 which is mounted outside of and distinct from tube 25 may take the form of a bimetal strip which bends in response to temperature variations. A magnet 46 is arranged to bear against arm 45 through the integral pin 47 which is drawn toward arm 45 by spring 48 and pin 49.

When magnet 46 is brought toward arm 40, said arm 40 will be attracted thereto so as to produce pivotal movement of the bell crank lever 50 about pin 42 and swing the grid 39 into the electron stream. This position of the grid 39 is shown in broken lines in Fig. 3. Conventional grid bias, not shown, between the cathode 37 and grid 39 is provided so as to produce grid control of the electron stream. The ensuing reduced current flow in the plate circuit may be caused to actuate or de-actuate a heat or cold producing apparatus which may then react upon thermal responsive arm 45 so as to permit the withdrawal of the magnet 46. The grid 39 is then swung back out of the electron stream when a balance has been reached between the movement of the arm and the effect of the apparatus controlled by the tube. However, whether or not the reduced plate current is caused to move the arm 45, it will be apparent that any temperature produced changes in the arm 45 will be reflected by variations of plate current flow as the proximity of the magnet 46 to the arm 40, and the magnetic action thereon 60 is accordingly intensified.

Arm 45 may alternatively take the form of an ordinary fixed bracket member. Accordingly, articles the thickness of which it is desired to determine, may be inserted between pin 47 and arm 45 so as to move magnet 46 forward against

the action of the spring 48. This will produce movement of the bell crank lever and interposition of the grid 39 into the electron stream to a degree depending upon the thickness of the inserted article. Such thickness can then be read from a calibrated plate current meter in the circuit of anode 36.

In the embodiment of Fig. 3, the tube 35 may be a gas-filled tube, if desired, or it may normally be a rectifier using only the cathode and anode elements functioning as an ordinary diode arrangement and capable of handling heavy currents. The introduction of the grid 39 into the electron stream, however, is effective in converting the tube from an effective diode to a triode. The bell crank lever serves to amplify the movement of arm 40 as the grid is caused thereby to travel in a path between the anode and cathode electrodes. Thus the transverse position of the grid in the electron stream between these electrodes determines the controlling effect thereof as in the previous embodiment.

Referring to Fig. 4, a tube construction is shown which varies the grid control between the cathode and anode by a rotating action of the grid structure. Thus, tube 50 is illustrated as having a plurality of anodes 51 which may be interconnected either internally or externally of the tube. Cathode 52 constitutes, as hereinbefore mentioned, the source of electrons which flow towards the anodes. The control grid 53 is rotatably mounted within the tube in a manner illustrated in Fig. 5. The grid 53 comprises a shell or circular wall of thin metal having a series of openings or discontinuities 54 formed therethrough, the number of which corresponds to the number of anodes 51 in the tube.

Grid 53 has a reduced portion or neck 55 which is formed with a ball 56 supported and rotatably mounted in the knuckle 57. Knuckle 57 may be connected or be integral with a grid cap 58 so that bias potential to the grid 53 may be applied through the cap 58, knuckle 57 and ball 56 thereto. Such construction effectively suspends the grid 53 within the tube and permits rotation thereof for variation of its control functions. The knuckle 57 may have flattened socket portions as shown so that the grid 53 will not tilt but will rotate only, or any conventional manner of preventing such tilting may be employed.

In order to produce rotation of grid 53, a wire 59 may be curled around neck 55 and connected thereto at point 60. Wire 59 is connected at its other terminal 61 to arm 62. Arm 62 is pivoted at 63 within the tube so that pivotal movement of arm 62 actuates wire 59 so as to rotate grid 53. Arm 62 is provided with an armature member 64 adapted to be attracted to an externally located magnet such as the magnet 46 in the previous embodiment. Wire 59 may take the form of a coiled spring whose normal function is to maintain arm 62 in a rearward position where the wire 59 is wound around neck 55. Attraction of armature member 64 by the magnet is therefore effected against the action of spring wire 59.

When the grid 53 is rotated as hereinabove set forth, it will block the path of the electrons by presenting the bias potential thereto. Only slight movement of the grid is necessary to effect such action because such slight action is multiplied by a factor of 5, there being 5 anodes and associated grid portions in the illustrated embodiment. Thus, the grid need rotate only approximately 35 degrees in order to proceed from

absence of control to complete control. It is apparent, however, that the number of anodes and grid openings may be varied as desired. As the grid rotates from the position shown in Fig. 4, the position of the discontinuities 54 thereof is varied and they are brought out of alignment with the anodes whereby grid control is correspondingly rendered effective.

In Fig. 6 is illustrated a tube structure wherein two sets of anodes are provided so as to permit a differential flow of electrons thereto. Thus, tube 70 is provided with the anode sets 71 and 72 each being connected into a separate circuit. Anodes 71 are interconnected so as to form a first anode structure. Anodes 72 are staggered in relation to anodes 71 and form a second anode structure. The grid 73 is constructed in a manner similar to that of grid 53 in the previous embodiment so as to intercept or permit the flow of electrons from cathode 74 to anodes 71 or 72 differentially. Anodes 71 and anodes 72 will have different load resistors so that the position of grid 73 will be reflected by the amount of current flowing in these load resistors or the voltage drop across them. This effect will be differential so that the tube may be used either in a Wheatstone bridge or push-pull arrangement.

When grid 73 is so oriented as to cut off the flow of electrons to anodes 71, it permits the flow of electrons to anodes 72 and vice versa. Intermediate positions are also provided wherein each of the anode sets receives a portion of the electrons.

It will be seen from the foregoing that I have provided an electron tube wherein a grid element is mechanically or physically varied to alter its effective area, through conditions originating externally of the tube and transmitted to the grid element through a rigid tube envelope structure which is not provided with special tube envelope formations or flexible diaphragms therein. However, the invention is not to be limited to actuation of control grids since a screen grid may well be treated by the present invention as may be anode structures which may be moved relative to a controlled electron path. Such an arrangement as well as the embodiments above mentioned may well operate as a volume control in radio apparatus since the current flowing in the anode circuit is controlled thereby. Thus, the usual volume control potentiometers or variable resistors may be dispensed with. In addition, while I have shown a permanent magnet for actuating the grid lever in Fig. 3, it is apparent that an electromagnet may be substituted therefor and the intensity of the magnetic field thereof may be varied through variations in proximity thereto to the grid lever or through variations of current flow in the electromagnet. Therefore, it is intended in the following claims to cover all such changes and modifications as fall within the true spirit and scope of the invention, such as, for example, described above or hereinafter.

In the event that an electromagnet is utilized instead of a permanent magnet, such electromagnet may well be disposed within the tube envelope with the leads therefrom being connected to the usual base pins. Thus, a signal which is applied to the internal electromagnet will act upon the grid structures such as shown in Figs. 3 to 6 so as to produce a considerable change of plate current flow in response to the small variations of current. The proximity of an internal electromagnet to the grid structure will thus pro-

vide very high degrees of amplification particularly with the light weight grid which is easily actuated. With such a construction it is also feasible to apply the signal to the grid as a potential thereon while simultaneously applying it as a current to the electromagnet so that a double action is achieved and extremely high amplification effected, particularly when heavy currents are being handled by the tube.

1. An electron tube having cathode and anode electrodes, physically variable control grid means for controlling the electron stream between said electrodes, said control grid means comprising a hollow tube of electrically non-conductive material disposed within said tube and substantially between said electrodes, a conductive liquid within said tube which rises or falls in response to conditions external of said tube, means to apply grid bias potential to said liquid whereby the effective area of said bias potential rises or falls in accordance with said external conditions, said rise or fall being adapted to longitudinally vary the effective control grid area in said electron stream whereby the controlling effect of said control grid means is varied accordingly.

2. Apparatus according to claim 1 wherein said control grid means comprises a mercury thermometer having a portion thereof extending outside of said tube.

3. Apparatus according to claim 1 wherein said control grid means comprises a spirally arranged mercury thermometer disposed around said cathode electrode and having a mercury supply reservoir extending outside of said tube, said grid bias potential being applied to the mercury in said supply reservoir.

4. An electron tube having elements for pro-

ducing an electron flow therein, an electrode in said tube adapted to influence said electron flow by having a potential thereon, and means to vary the effective physical position of said electrode, said electrode comprising a hollow tubing of electrically insulating material, an electrically conductive liquid adapted to rise and fall in said tube in response to conditions existing externally of said tube and adapted to have said potential applied thereto, mutually spaced metallic areas disposed externally of and continuously up said tubing so as to be separated by lengths of the electrically insulating material of said tubing and communicating with said conductive liquid whereby said potential is transmitted to a number of said areas in accordance with the degree of rise of said liquid, the number of said areas having said potential transmitted thereto representing the degree of influence of said electrode.
